CLAIM

The ornamental design for a flexible animal perch, as shown and described.

DESCRIPTION

FIG. 1 is a front elevation view of a flexible animal perch showing my new design;

FIG. 2 is a rear elevation view thereof;

FIG. 3 is a left side elevation view thereof, the left side being identical;

FIG. 4 is a top plan view thereof, the bottom plan view being identical;

FIG. 5 is a front elevation view of my flexible animal perch in an arched position, the rear elevation view being identical;

FIG. 6 is a top plan view of FIG. 5;

FIG. 7 is a bottom plan view of FIG. 5;

FIG. 8 is a right side elevation view of FIG. 5, the left side elevation view being identical;

FIG. 9 is a side perspective view of my flexible animal perch in a curved configuration;

FIG. 10 is a side perspective view of my flexible animal perch in a circular configuration; and,

FIG. 11 is a right side elevation view, of a second embodiment of FIG. 1 that differs from FIG. 1 only in the suction cup, the left side being identical.

The broken lines on FIGS. 1, 3, 4, 5, 7, 10 and 11 indicate release tabs and are for illustrative purposes only and form no part of the claimed design.
